APPARATUS FOR CONTROLLING ELECTRIC CIRCUITS

George M. Stapleton, New York, N. Y., assignor to Ward Leonard Electric Company, a corporation of New York

Application March 21, 1941, Serial No. 384,485

23 Claims. (Cl. 74—471)

This invention relates to the control of electric circuits by adjustment of a suitable form of controlling device which will change the value of the current in the controlled circuit, such as by means of an adjustable resistance device or rheostat. The invention is particularly applicable to the control of lighting circuits in theaters and the like and for various spectacular productions where it is desirable to produce various lighting effects by a plurality of lamp circuits, although the invention is applicable to other purposes where it is desired to affect a plurality of electric circuits in various ways and in various combinations selectable at will.

In securing various lighting effects, a number of lamp circuits are provided which may have lamps of different colors in the respective circuits and variously located so as to give desired illuminating effects in various different scenes in sequence; and in a certain scene it may be desired to have the lamps of some circuits at half bright and others at full bright and others at various intermediate degrees of illumination, whereas in the next scene certain of said circuits may be desired to be of the same or different illumination and additional lamp circuits may be utilized variously controlled to give desired scenic effects. Likewise, subsequent scenes may require different control of the individual circuits and utilize certain of the circuits which may or may not have been used in prior scenes. In passing from an existing scene to the next scene, the controls should be such that the lighting of the existing scene is gradually changed proportionately in the different circuits of that scene so that the relative lighting effects of that scene are approximately maintained during the change; and likewise the lighting effects of the next scene should be gradually changed to the desired illumination of that scene and during such change, which takes place simultaneously with the change of the prior scene, the relative lighting effects during the passing to the second scene should be approximately maintained. This transfer is generally known as fading.

In addition to the set-ups of the different scenes and the transfer above referred to, it is also desirable to change the lighting effects in any one scene to any degree desired and to return to the lighting condition of such scene, or to adjust the degree of lighting to any desired condition. This is accomplished by a master which simultaneously controls the different circuits and such control should be accomplished so that the lighting of the controlled circuits is

changed proportionately by the master so as to maintain approximately the relative lighting effects. Furthermore, it is desirable to enable the master to control any selected circuits of a given scene without controlling other circuits and this is accomplished by enabling and disabling devices to give any desired selectivity of control by the master. Also, the masters should be provided so that they may selectively control the circuits of any scene and in some cases the requirements may be such that the masters are selectively controlled by grand masters. The provision of controlling means of the above character permits the obtainment of various combinations of lighting effects and the control thereof in various ways to fulfill the requirements of theatrical and spectacular productions.

The main object of this invention is to provide apparatus for accomplishing the above described control of circuits by apparatus of comparatively simple form of construction of the various parts and which will be dependable and durable in operation and insure positive operation of the parts in the manner desired. Another object is to accomplish this by providing means for the control of individual circuits respectively so that the wiring connections to the control board will be simple and not involve complicated inter-connected circuits and the use of a large number of electrical controlling devices of various character. Another object is to provide means of a character which may be adapted for the control of a comparatively small number of circuits, or adapted to be built up to control any number of circuits desired and to provide for master control and grand master control as may or may not be required in various installations. Other objects and advantages will be understood from the following description and accompanying drawings.

Fig. 1 is a side elevation of a circuit controlling panel; Fig. 2 is likewise a side elevation but with certain parts removed from the panel; Fig. 3 is similar to Fig. 2 except showing the parts shifted to a different scene; Fig. 4 is similar to Fig. 1 except the enabling means is shifted to make the master control effective in one scene; Fig. 5 is a section on line 5—5 of Fig. 1; Fig. 6 is a section on line 6—6 of Fig. 4; Fig. 7 is a face view of certain controlling parts; Fig. 8 is an edge view thereof; Fig. 9 is a horizontal section on the line 9—9 of Fig. 4; Fig. 10 is a horizontal section on the line 10—10 of Fig. 4; Fig. 11 is a front view of two sets of panels with master and fader control; Fig. 12 is a front view of two sets of

panels with interlocking masters, grand master and fader control; Fig. 13 is a side elevation showing the interlocking masters; Fig. 14 is a horizontal section on the line 14—14 of Fig. 13; Fig. 15 is a side elevation showing the grand master panels; and Fig. 16 is a front elevation of the shafts at the rear of the master and fader panels of Fig. 12 showing the connections thereto.

Fig. 1 shows one panel unit for controlling its individual related electric circuit. It is adapted to extend vertically and its main support is in the form of a sheet metal plate 1 bent at its front portion to form the face 1a of the panel. It is provided with projecting ends 1b for fastening to a skeleton frame which may support any desired number of panels side by side, or in rows above and below each other. A second plate 2 is supported on the main plate and spaced in front of it by screws and spacing sleeves 2a. The second plate covers only the upper portion of the main plate and supports the parts for the setting of scene 1 and the parts for enabling and disabling master control for scene 1 while the upper portion of the rear plate supports the parts for the setting of scene 2 and the enabling and disabling means for master control of scene 2. The lower portion of the main panel supports the circuit controlling device and the fader control for shifting from one scene to the other.

Fig. 11 is an illustration, as an example, of two rows or sets of panels as shown in Fig. 1, there being three such panels in the upper row at the left and three in the lower row at the left. Adjoining the panels of the upper row are two master panels 3a and 3b and adjoining the panels in the lower row are two master panels 3c and 3d. Adjoining the master panels of the upper row is a fader panel 4. Obviously any number of individual circuit controlling panels 1a may be assembled side by side and in any number of rows according to the requirements of any particular installation.

Referring now to Fig. 1, in the lower portion of the panel is shown a slidable sheet metal plate 5 which is supported upon the main panel and spaced therefrom by three screws and sleeves 5a. These screws project through three horizontal slots 5b in the plate and under the heads of these screws are washers for retaining the plate in position. The plate is slidable from the position near the front of the panel towards the rear of the panel to the position shown in Fig. 3, the supporting screws serving to limit movement of the panel in the two extreme positions. Extending rearwardly from the upper left-hand corner of the plate, as shown in Fig. 1, is a pin 5c. This is engaged by the slotted end of an arm 5d, the upper end of which is pivotally supported on the plate 1. The arm 5d has connected thereto a second arm 5e which extends rearwardly beyond the panel and is controlled by operation of the fader shaft.

The plate 5 carries the device for controlling the individual circuit of this panel. In the present instance this is shown as a variable resistance device in the form of a tubular unit 6. This is formed of a central insulating support, as shown in Fig. 5, around which is wound the resistive conductor making up a large number of turns from one end to the other of the unit. This conductor is suitably insulated between adjacent turns and on its external surface preferably by vitreous enamel. At the front of the tube is formed a projection for the purpose of projecting the turns of wire along a line; and along this

line the enamel is removed so as to expose a portion of the wire at each turn giving a large number of adjoining contact surfaces 6a along the front of the tube. The tube is provided with a terminal 6b at each end for connecting the resistive conductor in series with the circuit to be controlled. The tube is supported at each end by a metal strip 6c which is cut out from the plate 5 and bent at right-angles to engage and support the tube in spaced position from the plate.

A bow-shaped contact bar 7 engages the row of contact surfaces 6a at its extreme ends in the resistance-all-out position, as shown in Fig. 1; and as this bar is moved upwardly it gradually increases the resistance in the controlled circuit until the central portion or apex of the bar 7 engages the middle of the row of contacts, as shown in Fig. 4, at which time all of the resistance of the device 6 is connected in series in the controlled circuit. It is this variable movement of the contact bar 7 which influences the change of lighting effects of the controlled circuit; and this resistance may control the lamp circuit directly, or through saturable reactors or in any other of the well known ways.

The contact bar 7 is carried by a block of insulation 7a which in turn is carried by the lower end of a screw 7b. This screw has a threaded engagement with a metal block 7c, as well shown in Fig. 5, which in turn is carried by the lower end of a metal strip 7d, the upper end of which has inwardly turned ears 7e at opposite sides which embrace a block 7f. This block carries a pin 7g on which the ears 7e are pivotally supported. A metal strip 7h is fixed at its upper end to the bottom of the block 7f and extends downwardly over the plate 5. This strip 7h is slidably mounted on the plate 5 upwardly and downwardly, such movement being permitted by vertical slots 7i, as shown in Fig. 6 and is guided in its movement by washers and screws 7j which pass through the strip and are fixed at their inner ends to the plate 5. A tension spring 7k is secured at one end to the face of the strip 7h and at the other end to the under side of the strip 7d for the purpose of yieldingly holding the contact bar 7 in good electrical contact with the contact surfaces 6a of the resistive unit. In view of the contact bar being supported by the screw 7b which may turn in the block 7c, it results that the pressure exerted by the spring 7k will be imposed equally on the two arms of the contact bar 7 and thereby insure uniform contact engagement in all positions of the contact bar. The screw 7b also serves as a means for adjusting the contact bar to its proper position which may be accomplished by turning the strip 7d on its pivot upwardly and then turning the contact bar until the desired inward or outward adjustment of the screw 7b is obtained.

The upper end of the contact strip 7h carries on its inner face a projecting pin 7m; and it is by actuation of this pin upwardly or downwardly that variable control of the circuit is obtained. This action results from the fact that when the pin 7m is moved it will move the plate 7h and also the supporting block 7f which in turn moves the contact strip 7d and contact bar 7. Thus these parts form a vertically movable unit for changing the amount of resistance in the controlled circuit by adjustment of the contact bar in the manner already described.

The means for adjusting the contact bar 7 to any vertical position for obtaining a desired lighting effect of the particular circuit controlled

in the different scenes will now be described. Referring to Fig. 1, the handle 8 for adjusting the contact bar for say the first scene, is at the front of the narrow portion 1a of the panel plate and is mounted on a disk 8a which is rotatably mounted upon a screw and spacing sleeve 8b fixed to the plate 2. The disk is spaced a short distance from the plate 2 and is provided with a radially extending slot 8c. A pin 8d extends into this slot from the rear of the disk, the pin being fixed to a slidable strip 9 of metal which extends horizontally across the plate 2. It is provided with a pair of longitudinal slots 9a through which extend screws 9b which are fixed at their inner ends to the plate 2 and serve to guide the strip 9 in its longitudinal movement. It is evident that the movement of the handle 8 will, through the pin connection with this strip, cause the movement of the strip to any desired position.

The strip 9 carries a trough-shaped element 10 which is pivotally mounted at about its center by a rivet pin 10a, the inner end of the pin being fixed to the strip 9. The rear end of the element 10 carries a pin 10c which projects outwardly from the same and engages a slot 11a in another plate 11 which is spaced from and supported by the plate 2 by sleeves and screws 11b, as well as by the left-hand screw 9b. The plate 11 is slidable vertically on these supporting screws, this being permitted by providing slots 11c in the plate 11; but for the present, the plate 11 may be considered fixed in the position shown in Fig. 1. Another metal strip 12 extends over the slidable strip 9 and is bent at right-angles toward the plate 1 through an opening in the plate 2 provided by a cut-out portion from this plate, and the strip 12 then is again bent at right-angles and extends downwardly along the surface of the plate 1. It is vertically movable and is guided by a screw and spacing sleeve 12a at its upper end and a screw 12b at its lower end, slots 12c being provided in the strip 12 for permitting vertical movement. The strip 12 is provided with a side projection to which is fixed a pin 12d which projects inwardly to engage the trough of the element 10. The strip 12 has a side projection near its lower end which carries a pin 12e fixed thereto and which extends outwardly from the strip. The pin 12e engages one end of a guiding trough 13 through a slot in the right-hand end of this guide, the head of the pin being enlarged to extend over the edges of the slot and thereby retain this end of the guide in position. The opposite end of the guide 13 is similarly connected by a headed pin extending through its slotted end for holding that end of the guide in any adjusted position, as will later be described.

The pin 1m which has already been described as extending inwardly from the end of the block 1f, projects within the trough of the guide 13. It follows that with this pin 1m positioned in the front end of the guide 13, as shown in Fig. 1, any movement of that end of the guide will serve to control the position of the contact bar 7. This control is secured by movement of the handle 8. With the parts positioned as shown in Fig. 1, the contact bar 7 is in its lowest position and all of the resistance of the controlled circuit is short-circuited by this bar giving a condition corresponding to full bright of the controlled lamp circuit. When the handle 8 is moved downwardly, it moves the strip 9 toward the front of the panel and in view of the trough 10 being connected to the strip 9 by the pin 10a, it will cause the trough 10 to likewise move toward the front of the panel.

During this movement the element 10 will maintain its angular position shown in Fig. 1 by reason of its pin 10c passing in the horizontal slot 11a and thereby preventing any rotation of the element 10 around its pivot pin. As the element moves toward the front of the panel, the pin 12d is gradually forced upwardly which in turn causes the strip 12 to slide upwardly. The upward movement of this strip by its pin connection with the front end of the guide 13 causes the right-hand end of this guide to move upwardly; and the engagement of the pin 1m with this guide results in the upward movement of the parts carrying the contact bar 7. When the handle 8 has been moved down to its lowest position, the action just described results in the contact bar being moved to its upper extreme position corresponding to that shown in Fig. 4. At that position of adjustment, all of the resistance is effective in the controlled circuit giving a condition corresponding to black-out of the lamp circuit. It is evident that by means of the handle 8, the contact bar may be adjusted to give any desired intermediate condition of the controlled circuit, such as half bright, three-quarters bright, one-quarter bright, or any other desired condition of the controlled circuit.

In addition to the parts already described as controlled by the handle 8, there is another set of similar parts controlled by the handle 14 which is fixed to a rotary disk 14a positioned at the side of the handle 8 and disk 8a. The parts controlled by the handle 14 are more particularly shown in Fig. 2. The disk 14a is rotatably supported on a screw 14b which is fixed at its inner end to the main plate 1, the disk being spaced somewhat from the plate. The disk is provided with a slot 14c. A pin 14d projects into this slot from the rear side of the disk, being carried by a horizontally extending slidable strip 15. This strip has a pair of slotted openings 15a through which extend supporting and guiding screws 15b, the inner ends of which are fixed to the plate 1. A trough-shaped element 16 is pivotally connected at about its center to the strip 15 by a pin 16a. One end of the element 16 carries a forwardly extending pin 16c which projects into a slot 17a of another sheet metal plate 17 which is supported by screws 17b and the left-hand screw 15b from the plate 1. The plate 17 is spaced from the plate 1 by spacing sleeves on the inner portions of the screws; and the plate 17 is provided with slots 17c to permit vertical movement of this plate on the guiding screws.

Another metal strip 18 passes over a portion of the plate 17 and extends downwardly and then is bent at right-angles toward the plate 1 and then is again bent at right-angles to extend downwardly over a portion of the plate 1. The ends of the strip 18 are provided with slots 18c and the screw 17b passes through the upper slot and a screw 18b passes through the lower slot which screws serve to guide the strip 18 in its vertical movement. A projection on one side of the strip 18 carries a pin 18d which extends into the trough of the element 16; and in the position shown in Fig. 2 the pin 18d coincides axially with the pivot pin 16a of the element 16. Another projection on the opposite side of the strip 18 carries a pin 18e which projects into the slotted end of the guiding trough 13, this end being the opposite end from that in which the pin 12e of the strip 12 projects. The head of the pin 18e is enlarged to retain that end of the guiding trough 13 in position.

Adjustment of this end of the guiding trough

is obtained by movement of the handle 14 in the same way that the opposite end of the guiding trough is adjusted by movement of the handle 8. In Fig. 2 the handle 14 is shown in its lowest position with the result that the pin 18e is in its uppermost position. When the handle 14 is moved upwardly it shifts the strip 15 from the position shown in Fig. 2 rearwardly from the front of the panel. In view of the element 16 being connected to this strip and in view of the upper end of this element being slideable in the slot 17a of the plate 17, the element 16 will be moved with the strip 15 in the angular position shown; and when thus moved, the pin 18d will pass along the trough of the element 16 resulting in the strip 18 being gradually moved in a downward direction. This in turn moves the pin 18e downwardly and thereby forces its end of the guiding trough 13 downwardly. This action in controlling the movement of this end of the guide 13 is the same as that already described with reference to moving the other end of the guide 13 by the handle 8. It is apparent that the two handles 8 and 14 adjust the two ends of the guide 13 respectively as may be desired, the adjustment by the handle 14 serving to determine the position of the contact bar 7 in scene 2.

The change from the assumed existing scene 1 wherein it was assumed that the lighting circuit of this panel was at full bright, to scene 2, is accomplished by the shifting of the plate 5 from the position shown in Figs. 1 and 2 to the position shown in Fig. 3. When this is done, the circuit controlling unit is carried bodily with the plate and results in the pin 7m being forced to travel along the trough of the guide 13 and gradually moved upwardly. This results in the contact strip 7d and contact bar 7 being gradually moved upwardly until the plate 5 has been moved to its limiting position, at which time the pin 7m will coincide with the axis of the pin 18e. The contact bar will thus be moved from the full bright position of Figs. 1 and 2 to the black-out condition of Fig. 3 at which time the apex of the contact bar is engaging the middle contact of the resistance unit and all resistance thereof is effectively in series in the control circuit. If, however, the handle 14 had been adjusted to say a mid-position instead of to its lowest position, the pin 18e, instead of being raised to its uppermost position, would have assumed a half-way intermediate position; and in that case the guide 13 would have been adjusted at a smaller angle and would have moved the contact bar from the extreme position of Figs. 1 and 2 to a half-way position which would have resulted in the controlled circuit being changed from full bright to a half bright condition.

After the shifting of plate 5 to scene 2 as controlled by the handle 14, the handle 8 may be re-set for the required condition of the circuit controlled by this panel for scene 3. When scene 2 is completed the plate 5 is shifted from the position shown in Fig. 3 back to the position shown in Figs. 1 and 2 which results in the controlled circuit being adjusted according to the setting of handle 8 for scene 3. Similarly after the completion of scene 2, the handle 14 may be re-set for the condition required for scene 4 and the shifting of the plate 5 after the completion of scene 3 will result in the controlled circuit being made to conform to the new adjustment of handle 14 for scene 4. In the same way the changes to subsequent scenes are obtained, each of which is determined by the setting of the handles 8 and 14.

In the passing from one scene to the next by the shifting of plate 5, there results a proportional change of the circuit from an existing condition to the subsequent condition of the controlled circuit which occurs gradually throughout the movement of plate 5. That is, passing from the full bright condition of Figs. 1 and 2 to the black-out condition of Fig. 3, the condition of the controlled circuit was gradually changed during the full movement of the plate 5; but if the adjustment of handle 14 had been such as to give a half bright condition for scene 2, then in passing from the full bright condition of scene 1 to the half bright condition of scene 2, the change would have taken place gradually throughout the full movement of the plate 5, giving a proportional dimming from the full bright condition to a half bright condition. The same proportional change throughout the full movement of the plate 5 would occur from any adjustment of one scene to the adjustment of the next scene. When a number of such panels are simultaneously controlled, in passing from one scene to the next, each circuit of the respective panels is similarly, gradually and proportionally changed through the full movement of the plates 5, giving the condition commonly known as fading. In this way the lighting intensities of the circuits of one scene are gradually and proportionately changed to the predetermined lighting intensities of the circuits of the next scene.

Referring to Fig. 1, it has already been explained that the plate 5 of each panel is shifted by movement of the arm 5e. This is in turn controlled by turning the fader shaft 19 which is suitably supported at the rear of the panels and is extended to pass by the rear of each panel of the assembled sets of panels, as shown in Fig. 11. At the rear of each panel an arm 19a extends from the fader shaft and each of these arms carries a pin 19b which engages a slot in the end of the arm 5e of each panel. It is evident that turning the shaft 19 will cause the simultaneous actuation of the plates 5 of each panel and thereby cause all the respective circuits of each panel to be controlled in the shifting from any one scene to the next scene. At the right of Fig. 11 is shown the fader panel for control of the shaft 19. From the front of this panel a handle 20 projects which is secured to a disk 20a which extends partially through a slot in the front portion of its panel. This disk is rotatably supported at its center by a spacing sleeve and screw 20b, as indicated in Fig. 1, one end of the screw being fixed to the side plate of the fader panel. A link 20c is connected at one end to a pin 20d on the disk 20a and at its other end to an arm 20e fixed to the fader shaft 19. It follows that movement of the fader handle 20 from its upper position shown in Fig. 1 to its lower position, as shown in Fig. 3, results in turning the fader shaft in a counter-clockwise direction and thereby shifts the plate 5 of each panel from the position shown in Fig. 1 to the position shown in Fig. 3, thus passing from the scene controlled by the handles 8 of each panel to the next scene controlled by the handles 14 of each panel. Similarly after the handles 8 have been re-adjusted for a later scene, the movement of the fader handle 20 from its lower position to its upper position will result in transferring from the scene determined by the handles 14 to the scene determined by the handles 8. 75 In case there are two sets of panels, one above

the other, as shown in Fig. 11, the fader shaft of the upper set of panels is extended and provided with an arm 20*f* which in turn is connected to a link 20*g* which is connected to an arm 20*h* of the fader shaft 19 of the lower set of panels. In this way, movement of the fader handle 20 of panel 4 will cause the simultaneous movement of the plates 5 of the upper set of panels as well as of the lower set of panels, giving simultaneous control of all the circuits in passing from one scene to the next.

In Fig. 11 there are two handles 21 and 27 at the top portion of each circuit controlling panel 1*a*. These are enabling and disabling handles for determining whether or not the circuits of each scene are made subject to the control of masters. When these handles are down, as shown in Fig. 11, the circuits are not subject to control by the masters but when these handles are up, or any selected one or more are up, such circuits are then subject to control by the masters. The means for accomplishing this result will be understood by reference to Fig. 1 which shows the handle 21 in its lower position. The handle is secured to a disk 21*a* which projects partially from the front portion of the panel and is rotatably mounted on a screw 21*b* and spacing sleeve for positioning the disk a short distance from the plate 2. The inner end of the screw 21*b* is fixed to the plate 2. The disk is provided at its periphery with a radial slot 21*c*. A triangular piece 22 of sheet metal is pivotally mounted at its lower end on a screw 22*a* and a spacing sleeve to position this piece from the plate 2 so that one end of this piece will extend over the portion of the disk 21*a* where the slot 21*c* is located. At this end of the piece 22 is a pin 22*b* which extends inwardly to engage the slot 21*c*. On the side of the disk 21*a* which faces the plate 2, are a pair of screws 21*d* which support the ends of a spring wire 21*e*. This spring wire passes under the slot 21*c* and engages the pin 22*b* so as to give a snap action when the handle 21 is moved to either of its two positions. The other end of the triangular piece 22 has connected thereto a metal strip 23 which extends horizontally toward the rear of the panel and carries at its end a pin 23*a* which extends toward the plate 11 and passes through and beyond a slot 11*d* in this plate. A sheet metal arm 24 is pivotally mounted at its front portion on the plate 2; and when the pin 23*a* is in the position shown in Fig. 1, it coincides with the axis of the arm 24. This arm extends beyond the plate 1 and its outer end is provided with a slot 24*a*. This slot is engaged by a pin 25*a* carried by an arm 25*b* on the master shaft 25. It is evident that rotation of this master shaft will result in rotation of the arm 24 about its pivot. Fixed to the mid-portion of the arm is a sheet metal piece 26 which is bent at an angle to cause its front portion 26*a* to extend under and close to the inner side of the plate 11. The front portion of the piece 26 is provided with an open ended slot 26*b* and into which the inner end of the pin 23*a* projects. When the pin 23*a* is in the position shown in Fig. 1, it is in the portion of the slot 26*b* that is most distant from the front of the panel. When the parts are in this position, any rotation of the master shaft 25 will have no effect on the control of the circuit of this panel because, although the master shaft will turn the arm 24 and its strip 26, no other parts will be actuated because the pin 23*a* is over the axis of the arm 24. Furthermore, at this position of the

parts, the plate 11 is necessarily positioned to fix the guiding element 10 at the proper angle to permit full range of circuit control by the set-up handle 8.

5 When the handle 21 is moved upwardly from the position shown in Fig. 1, the slot 21*c* engaging the pin 22*b* causes the triangular piece 22 to be turned clockwise. This moves the strip 23 toward the front of the panel and causes the pin 23*a* to move to the front of the slot 11*d* in the plate 11 and to the front of the slot 26*b* in the piece 26. Under these conditions, a counter-clockwise turning of the master shaft 25 will, by the clockwise turning of the arm 24, move the pin 23*a* downwardly because this pin is then at a distance from the axis of the arm 24. The downward movement of the pin 23*a* causes the downward movement of the plate 11 and the parts will then assume the position shown in Fig. 4.

10 The downward movement of the plate 11 is thus controlled by the master shaft when the enabling handle 21 is in its upper position. In Fig. 1, as already explained, the fader shaft 19 is in such position that the controlled circuit is on scene 1 as affected by the handle 8, giving a condition corresponding to full bright of that circuit. But when the plate 11 is moved downwardly by actuation of the master shaft 25, the control of the circuit is changed to give a dimming of the lamp circuit; and when the master shaft has been turned to its limit, the circuit will be brought to a black-out condition. This is shown by the position of the contact bar 7 in Fig. 4 because at that time the contact bar has been moved upwardly to insert all of the resistance into the controlling circuit.

15 This movement will be understood by referring to Fig. 1. The plate 11 is there shown in its uppermost position and when moved down by the master shaft, it forces pin 10*c* down which projects within the slot 11*a* of the plate. On account of the element 10 being pivoted at 10*a* on the strip 9, the downward movement of the pin 10*c* causes the opposite end of the element 10 to move upwardly. It thereby forces the pin 12*d* on the strip 12 upwardly and by reason of its pin 12*e* being connected to the guiding trough 13, it results that the pin 7*m* is caused to move upwardly and thereby move the control element to its resistance-all-in position with the parts as shown in Fig. 4.

20 In the foregoing it has been assumed that in passing to master control by movement of the enabling handle 21 upwardly, the master shaft was in its limiting position corresponding to full illumination. However, if the master shaft had been in some intermediate position, then when the enabling handle 21 was moved upwardly, it would force adjustment of the circuit controlling device to a condition corresponding with the intermediate setting of the master shaft. This is due to the fact that when the master shaft is in an intermediate position, the slot 26*b* is at an angle to the slot 11*d* of the plate 11; and when the enabling handle 21 is moved upwardly and forces the pin 23*a* along the inclined slot 26*b*, it necessarily moves the plate 11 upwardly by the action of the pin 23*a* in the slot 11*d* of the plate. Furthermore, this movement gives a proportional adjustment of the circuit controlling device according to the position of the master shaft. For example, if the set-up handle 8 had been set at a three-quarters bright position, and the master shaft at a half bright position, then movement of the enabling handle to make the

master control effective, would result in dimming the circuit from three-quarters bright to half of three-quarters bright, or three-eighths bright. It follows also, that when the enabling handle is moved to render the master ineffective, then, whatever the position of the master shaft, the circuit controlling device will necessarily assume a position corresponding to that of the set-up handle 8 and permit full range of control by the set-up handle 8 to any position desired. This is due to the fact that when the enabling handle is moved to its lower position, it moves the pin 23a to a position over the pivot of the element 24, thereby bringing the plate 11 to the position shown in Fig. 1 and moving the guiding element 10 to the angular position that determines the contact setting according to the position of the handle 8 whatever it may be. Also, this setting of the element 10 permits full range of control by the handle 8.

A similar or duplicate set of parts is provided for enabling master control when the fader has been shifted to make effective the scene controlled by the set-up handle 14. Thus referring to Fig. 2, there is an enabling and disabling handle 27. The handle 27 is fixed to a disk 27a supported by a screw 27b, the disk being provided with a slot 27c and screws 27d for supporting the spring 27e. These parts correspond to those described with reference to Fig. 1. There is also a triangular piece 28 pivotally supported on a screw 28a engaging the plate 1 and carrying a pin 28b which enters the slot 27c. A strip 29 is connected to one corner of the triangular piece and extends over the plate 17 and carries a pin 29a which passes through a slot 17d in the plate 17. An arm 30 which has an open ended slot 30a is pivotally supported on the plate 1, the center of this pivotal support coinciding with the pin 29a in the position shown in Fig. 2. A second master shaft 31 which extends back of all the panels carries an arm 31b which in turn carries a pin 31a engaging the slot 30a. The arm 30 has fixed thereto a sheet metal element 32 which has a portion 32a offset from the arm and provided with an open ended slot 32b at its end. The pin 29a of the strip 29 is prolonged to engage the slot 32b, these parts all being similar to those described with reference to Fig. 1.

With the parts in the position shown in Fig. 2, the turning of the master shaft 31 in a counter-clockwise direction will have no effect on the control of the circuit because the pin 29a coincides with the axis of the element 30 which permits full range of control by the set-up handle; but when the enabling handle 27 is moved from the position shown to its upper position, it shifts the strip 29 and its pin 29a to engage the other end of the slot 17d in the plate 17 and also shifts this pin 29a along the slot 32b at some distance from the axis of the arm 30 and then transfers the controlling device from its condition determined by the set-up handle only, to a condition proportionately modified according to the position of the master. Under these conditions the turning of the master shaft 31 in a counter-clockwise direction will shift the plate 17 downwardly and thereby actuate the circuit controlling element in the same manner as described with reference to Figs. 1 and 4.

However, the turning of the master shaft 31 will not affect the control circuit unless the fader shaft has been operated to shift the plate 5 to the position shown in Fig. 3; and it has already been explained that by reason of the handle 8

being set at full bright position and the handle 14 being set at black-out condition, the shifting by the fader resulted in bringing the control circuit from the full bright condition of Figs. 1 and 2 to the black-out condition of Fig. 3. Assuming the condition of Fig. 3 and the enabling handle 27 moved to its upper position, the turning of the master shaft 31 in a counter-clockwise direction will have no effect upon the circuit controlling element. This is due to the fact that this element 7, as shown in Fig. 3 is already at black-out position. The actuation of the plate 17 downwardly by the master shaft will move the pin 16c downwardly and turn the element 16 on its pivotal connection with the strip 15; but by reason of the fact that the pin 18d carried by the strip 18 has its axis coinciding with the axis of the pin 16a in this position, the rotation of the element 16 on its pivot will have no effect in actuating the element 18 and likewise no effect on the movement of the circuit controlling element.

Considering the effect of the master shaft 25 in shifting the controlling element from the condition of Fig. 1 to the condition of Fig. 4, it was explained that the result was to change the circuit controlling element from a full bright condition to black-out, whereas in considering Fig. 3 it was seen that the operation of the master shaft 31 had no effect on the circuit controlling element because this was already at black-out position. This shows the results when the set-up handles 8 and 14 are in the extreme limiting positions; but if either of these handles had been set to give the circuit controlling element an intermediate position, such as half bright or three-quarters bright, then the movement of its master shaft to its limiting position after being enabled, would have resulted in bringing the circuit controlling element from its assumed intermediate position to black-out position. This action would be due to the fact that the strip 9 or 15 would have taken the position corresponding to the set-up of the handle 8 or 14 and would have brought the element 10 or 16 to positions where the axes 45 of their pivotal points did not coincide with the pins 12d or 18d on their respective elements 12 and 18. Displacement of these pins from the axes of the elements 13 and 16 would correspond with the adjustments of the handles 8 and 14 and it would follow that whatever these adjustments might be, the master shafts would bring the circuit controlling element to the black-out position when the master shafts were turned to their limiting positions. Furthermore the change from an existing condition by the masters to the black-out condition is proportional throughout the movement of the master shafts. That is, if one circuit adjustment on one panel was at full bright, on another panel half bright and another panel one-quarter bright, the control by the master shaft would result in dimming the circuits proportionately so that the relative lighting effects of each circuit would be maintained approximately during the dimming by the master. When the master shaft is turned in the reverse direction, it will bring all of the circuits controlled thereby to a condition of illumination corresponding with the setting of the circuits. That is, from black-out condition it will bring each circuit controlled to full bright, three-quarters bright, half bright, or any other condition according to the setting by the set-up handles; and during this brightening of the lights, the increase in the lighting effects will be proportional with reference to each circuit, maintaining the relative il-

lumination in the same manner as occurred during the dimming of the lighting circuits. Also the master shaft, according to the amount it is turned, may dim the lighting effects proportionally to a partial dimming and then back to a condition corresponding to the set-up for particular lighting effects during an existing scene.

The two master shafts 25 and 31, as already explained, extend along the back of each circuit panel in any set, as shown in Fig. 11, and there is a master handle 33 and 34 for each of the two scenes of a set of panels. As there is a double row of panels, as shown in Fig. 11, there may be similarly master handles 33 and 34 for each row of panels. The master handles are fixed to rotatable disks 35 which extend forwardly somewhat from the master panels and are rotatably mounted on central screws fixed to the sides of the panels in the same way as the fader disk 20a is mounted. Figs. 1, 2 and 3 show the master handle 33 in its upper position, the master handles 34 being back thereof. The disk 35 of the handle 33 has connected thereto at a point displaced from the center of the disk, a link 36, the other end of which is connected to an arm 37 extending from the master shaft 25. Movement of the master handle 33 downwardly will thus cause the master shaft 25 to rotate in a counter-clockwise direction for the dimming of the lamp circuits which may happen to be controlled thereby; and the reverse movement will bring the condition of the lighting circuits to that corresponding with the set-up of the different panels. The disk 35 to which the handle 34 is connected similarly has a link 38 connected to it which in turn is connected to an arm 39 of the master shaft 31. It is evident that movement of the master handle 34 downwardly will give a counter-clockwise rotation of its master shaft for the dimming of the lamps on circuits which may happen to be controlled by this master shaft 31. In view of the fact that the circuit of each panel may be made subject to control by a master shaft by the movement of the enabling handles of the panels, it will be evident that in an existing scene any number of the enabling handles may be selectively moved to the enabling position and certain circuits thereby made subject to control of the master while others are not so controlled. In this way during each existing scene, certain of the lighting circuits may simultaneously be dimmed by a master shaft while others of that scene are not affected by the master shaft and remain at the illuminating condition corresponding to the position of the set-up handles.

In some cases it is desirable to provide grand master control in addition to master control of individual sections of panels. Under such conditions, the individual masters of the different sets are made subject to control by the grand masters or not, as desired. A structure for securing this form of control is disclosed in Figs. 12 to 16. Referring to Fig. 12, the individual circuit panels with set-up handles 8 and 14 and their enabling and disabling handles 21 and 27 are the same as already described. Likewise the fader panel with its handle 20 and connections to the fader shafts 19 are the same as before; but the master panels 40a, 40b, 40c and 40d of Fig. 12 include not only the master handles 41a, 41b, 41c and 41d but also the enabling and disabling handles 42a, 42b, 42c and 42d whereby the masters may, when desired, be subjected selectively to control by the grand masters. The

master panels of this character are herein designated as interlocking master panels. In Fig. 12 the two grand master panels for the different scenes are shown at 43a and 43b, the grand master handles being indicated at 44a and 44b.

Figs. 13 and 14 show the structure of the interlocking master panels, Fig. 13 showing two such panels 40a and 40c one above the other for the master control of each set of individual circuit panels. These masters are for the control of one scene and a similar pair of master panels 40b and 40d would provide master control for a different scene. The two master panels of Fig. 13 are duplicates of each other but are inter-connected for control by the grand master. Each of these interlocking panels includes a main sheet metal plate 45 having a portion bent at right-angles to form the narrow face of the panel. The master handle is connected to a disk 46 which is rotatably mounted at 46a upon the plate 45 being somewhat spaced therefrom and has a portion extending through the front of the panel. The disk is provided with a radial slot 46b. A metal strip 47 extends across the mid-portion of the plate and is provided with a pair of slots 47a which permit the strip to be moved toward and from the front of the panel, being guided by screws 47b which project through the slots and are fixed to the plate 45. A pin 47c carried by the front end of the strip projects into the slot 46b. A downward movement of the master handle 41a will cause the strip 47 to move from the position shown in Fig. 13 to the right by means of this slotted pin connection. A trough-shaped element 48 is pivotally mounted at 48a on the strip 47. The element 48 has a pin 48b at one end which projects into a horizontally extending slot 49a in a plate 49 which extends over the element 48 and strip 47. The other end of the element 48 is trough-shaped, the trough facing the plate 49. A vertically movable strip 50 extends under the end of the element 48 and carries a pin 50a which extends into the trough of element 48. The strip 50 is provided with a slot 50b at its lower end through which projects a guiding screw 50c fixed to the plate 45. The upper end of the strip 50 is connected to an arm 51 which is pivotally mounted at 51a on the plate 45. The end of this arm is provided with an open ended slot 51b which engages a pin 52a carried by a rocker arm 52 pivotally mounted upon the plate 45 by the screw 52b.

The rear end of the arm 52 has an open ended slot 52c which engages a pin on an arm 53 secured to the master shaft 25. The interlocking master panel adjoining the panel 40a is similarly formed for controlling a rocker arm 54 having an open ended slot 54a which engages a pin on an arm 55 connected to the master shaft 31.

In operation, the control of the master shafts individually results from the movement of their respective handles 41a to 41d, provided their respective enabling handles 42a to 42d are in their upper positions. The latter condition is shown in the lower part of Fig. 13 permitting master control by the master shaft 25 of the lower set of panels. Downward movement of the master handle 41c results in shifting the strip 47 toward the front of the panel and carries with it the element 48. With the plate 49 fixed in position, it results that the element 48 is maintained in the angular position shown as the pin 48b moves along the slot 49a. The movement of the element 48 toward the front of the panel forces the pin

50a downwardly and carries with it the strip 50. This turns the arm 51 in a counter-clockwise direction which thereby turns the rocker arm 52 in a clockwise direction and the master shaft 25 in a counter-clockwise direction. Such movement of the master shaft results in moving the circuit controlling element of each panel which is then subject to control by the master shaft, in a direction corresponding to the dimming of the lamps in the manner already explained. Movement of the master handle in the reverse direction restores the circuits to their original condition. This manner of master control applies to each one of the master handles, the upper master handles 41a and 41b controlling the upper master shafts 25 and 31 and the lower master handles 41c and 41d similarly controlling the lower master shafts 25 and 31 respectively.

The grand master control is obtained by the upward movement of the plate 49 of the interlocking master panels. At the back of each interlocking master panel is a pair of shafts 56 and 57, the shafts 56 being for grand master control of one scene and the shafts 57 being for grand master control of another scene. The plate 49 of each interlocking master panel is provided with vertical slots 49b through which pass screws 49c and one of the screws 47b which are fixed to the plate 45 and space the plate 49 from the plate 45. The slots 49b permit upward movement of the plate 49 on the screws. Such upward movement results in operation of its respective master shaft. For example, referring to the upper portion of Fig. 13, when the plate 49 is moved upwardly it carries the pin 48b upwardly which results in turning the element 48 on its pivot 48a and thereby, through the engagement of the pin 50a, forcing the strip 50 downwardly. This, as already explained, will turn the master shaft 25 in a counter-clockwise direction for controlling the individual panels which are subject to its control at that time. In the same way the master shaft 25 of the lower set of panels and the master shafts 31 of the two rows of panels would be operated by upward movement of the plate 49 of the interlocking master panels respectively.

The structure just described gives proportional control of the master shafts by the grand masters. For example, as shown in Fig. 13, the master handle 41a is in its uppermost position corresponding to full illumination of the controlled circuits. The strip 47 is then at its extreme inward position and the pin 50a is then at the end of the trough of the element 48. Consequently when the plate 49 is moved upwardly, the strip 50 is given its full movement downwardly; and this brings the controlled circuits from their existing condition proportionately to black-out condition. If, however, the master handle 41a had been brought to a position corresponding to half bright, then the pin 50a would take a position half way between the end of the trough of element 48 and its pivot 48a. Then movement of the plate 49 upwardly its full amount would result in moving the pin 50a and its strip 50 from its intermediate half-way position to its extreme lower position, resulting in control by the plate 49 from half bright position of the master to black-out. The return movement of the plate 49 would restore the pin 50a to its intermediate position. If the master handle 41a had been in its lowest position, then the pin 50a would take a position opposite the pivot 48a 75

of the element 48 and under that condition the upward movement of the plate 49 would have no effect in moving the strip 50, or the master shaft 25, as such parts would already be in the position of black-out. In other words, full movement of the plate 49 of each interlocking master panel gives proportional control of the master shafts from the positions in which they have been set by the master handles.

10 The plates 49 are controlled by movement of the grand master shafts 56 and 57. The shafts 56 have an arm 56a at the back of each interlocking master panel. These arms carry pins 56b which project within open ended slots of the arms 58 which are pivotally mounted on the plates 45. These arms are pivoted at 58a on the plates 45 and have fixed thereto offset portions 58b which have open ended slots 58c extending from over the pivotal center of the arms 58 to the front ends of the portions 58b. These parts are located between the plate 49 and the plate 45 and a pin 59a projects through a slot 49d in the plate 49 into the slot 58c. When the pin 59a is moved in the slot 58c so as to be over the pivot 58a of the arm 58, then rotation of this arm by the grand master shaft 56 has no effect upon movement of this pin; but when the pin 59a is positioned in the slot 58c at a distance from the pivot 58a, then rotation of the arm 58 by the grand master shaft will cause the pin 59a to move upwardly and thereby move the plate 49 upwardly. Thus operation of the grand master shaft will result in the movement of its plate 49 according to whether or not the pin 59a is displaced from the axis of the arm 58. The position of this pin 59a consequently determines whether or not the corresponding master shaft is operable by its grand master shaft.

40 The position of the pins 59a of the interlocking panels is determined by their respective enabling and disabling handles 42a to 42d. When one or more of these handles are down, it results that their corresponding master shafts are made subject to control of their grand master shafts. But when these handles are up, the master shafts are not subject to control of the grand master shafts. Referring to the upper portion of Fig. 13, the handle 42a is shown secured to a disk 60 which is pivotally mounted upon the plate 45 and a portion of the disk projects through an opening in the front portion of the panel. In a projection from the disk 60 is a slot 60a which is engaged by a pin 61a carried on the end of a metal strip 61. Another strip 61b is connected to this strip and is pivotally mounted at 61c on the plate 45. A horizontally extending metal strip 59 is pivotally connected to the lower end of the strip 61b, the strip 59 extending over the plate 49 and carrying at its inner end the pin 59a. Thus the movement 45 of the handle 42a will determine the position of the pin 59a and in the upper portion of Fig. 13 this pin is shown displaced from the axis 58a, giving an operative connection between the master shaft 56 and the plate 49, thereby making the master shaft 25 subject to control by the grand master shaft 56. However, when the handle 42a is moved to its upper position it will shift the connecting parts so that the pin 59a is over the pivot 58a. Under this condition the master shaft is not controlled by the grand master shaft. The lower portion of Fig. 13 shows the handle 42c in its upper position and its controlled pin 59a then coincides with the pivot 58a, showing the conditions when the related grand master shaft is ineffective in controlling its master shaft.

The relation of the master control to the grand master control is similar to the relation of the individual control of each circuit panel to the master control; and it follows that if the grand master shaft is in an intermediate position when a master shaft is operatively coupled thereto by the enabling handle, the master shaft will be caused to assume a condition corresponding with the intermediate set-up of the grand master shaft. Such movement gives a proportional adjustment of the master shaft according to the position of the grand master shaft. It also follows that when the enabling handle is moved to render the grand master ineffective, then, whatever the position of the grand master shaft, the master shaft will necessarily assume a position corresponding to that of the master handle and permit full range of control by the master handle to any position desired.

Referring to Figs. 12 and 15, the upper grand master shaft 56 for controlling when desired the upper master shaft 25, is extended beyond the upper interlocking master panels and provided with an arm 62 which is connected to a link 63. This link is connected to an arm 64 of the lower grand master shaft 56. The latter shaft extends beyond the interlocking master panels 40c and 40d and is provided with another arm 65 to which one end of a link 66 is connected. This link extends forwardly towards the grand master panel 43a and is pivotally connected at its front end to a disk 67 rotatably mounted upon the side plate 68 of the master panel. A portion of the disk 67 extends through an opening in the master panel 43a and has fixed thereto the grand master handle 44a. In Fig. 15 this handle is shown in its upper position and when moved downwardly will rotate the two grand master shafts 56 in a clockwise direction and thereby operate either or both of the master shafts 25, according to the position of the enabling handles 42a and 42c, as already explained. The grand master shaft 57 of the upper row of panels is provided with an arm 69 to which a link 70 is pivotally connected. The lower end of the link is pivotally connected to an arm 71 of the lower grand master shaft 57. This shaft is extended beyond the interlocking master panels 40c and 40d and provided with an arm 72 at its outer end. A link 73 is pivotally connected between this arm and the grand master disk 67 of the grand master panel 43b and is provided with a handle 44b for the simultaneous operation of the two grand master shafts 57.

It follows from the foregoing description with reference to the assembled panels of Fig. 12 that by means of the set-up handles 8 and 14 of the two rows of panels, two different scenes may be preset with any desired condition of the individually controlled circuits; that by means of the fader shafts and fader handle the change from an existing scene to the next scene is accomplished with proportional dimming of the one scene and proportional brightening of the next scene; that any individual circuit may be controlled as desired during an existing scene by movement of its set-up handle; that during each existing scene any selected number of the circuits may be subjected to control of a master by movement of one or more of the enabling handles 21 to their enabling positions for one scene and by movement of one or more of the enabling handles 27 to their enabling positions for the other scene; and that the masters may be subjected to simultaneous control by the grand masters when desired by movement of the enabling

handles 42a and 42c to their enabling positions for control by the grand master handle 44a for one scene and by movement of the enabling handles 42b and 42d to their enabling positions for control by the grand master handle 44b for the other scene. It is evident that any number of individual circuit controlling panels may be used and that they may be sub-divided into sections for selective control by masters for each section and that the masters of each section may be made subject to control by the grand masters selectively in the different scenes, giving a wide range of flexibility of control.

In the case of some installations, the fading control from one scene to another may not be required; and in that event there would be only one series of set-up handles applicable to all scenes. They preferably would be subject, however, to control by one or more masters and in some cases to further control by a grand master. The inter-relation between the set-up handles and the master shafts or shafts and between the grand master when used and the masters would be similar to that already described and give similar functional inter-actions.

Although certain embodiments of this invention have been described, various modifications may be made without departing from the scope thereof and may be varied to suit particular requirements.

I claim:

1. Apparatus for controlling an adjustable device for affecting a circuit, comprising a support, a set-up handle adjustably mounted on the support for selecting any desired adjustment of said device, an element actuated by movement of said handle to a position corresponding to the position of the handle, a guiding element pivoted on said first named element, a slidable element engaging said guiding element for adjusting said device upon movement of said handle, a holding element having a slotted portion for engaging said guiding element for holding the same from turning on its pivot, a pivoted actuator for moving said holding element for turning said guiding element on its pivot, a slidable connection between said actuator and said holding element movable from the pivot of said actuator to a portion thereof at a distance from the pivot, and means for adjusting said connection for making movement of said actuator effective or ineffective in actuating said holding element.

2. Apparatus for controlling an adjustable device for affecting a circuit, comprising a support, a pair of set-up handles adjustably mounted on the support for respectively selecting any desired adjustment of said device, a pair of elements actuated by movement of said handles respectively to positions corresponding to the positions of said handles, a pair of guiding elements carried by said first named elements respectively, a pair of slidable elements engaging said guiding elements respectively for adjusting said device upon movement of said handles, a guiding element the opposite ends of which are adjusted by said slidable elements, a slidable connection between said last named guiding element and the adjustable element of said device, and mechanical means for gradually shifting said slidable connection along said last named guiding element for moving the adjustable element of said device from the adjustment determined by one of said handles to the adjustment determined by the other of said handles.

3. Apparatus for controlling an adjustable de-

vice for affecting a circuit, comprising a support, a pair of set-up handles adjustably mounted on the support for respectively selecting any desired adjustment of said device, a pair of elements actuated by movement of said handles respectively to positions corresponding to the positions of said handles, a pair of guiding elements pivoted on said first named elements respectively, a pair of slideable elements engaging said guiding elements respectively for adjusting said device upon movement of said handles, a pair of holding elements for restraining said guiding elements respectively from turning on their pivots, a guiding element the opposite ends of which are adjusted by said slideable elements, a slideable connection between said last named guide and the adjustable element of said device, a pair of actuators for moving said holding elements respectively for turning said first named guiding elements on their pivots for adjusting said slideable elements respectively, and adjustable connections between said actuators and said holding elements respectively for making the movement of said actuators effective or ineffective in moving said holding elements.

4. Apparatus for controlling an adjustable device for affecting a circuit, comprising a support, a set-up handle adjustably mounted on the support for selecting any desired adjustment of said device, a slideable element actuated to a position corresponding to the position of the handle, a guiding element pivoted on said slideable element, a second slideable element engaging said guiding element for adjusting said device upon movement of said handle, an additional adjustable element having a pin and slot connection with one end of said guiding element for normally restraining said guiding element from turning on its pivot, an actuator, and coupling means between said actuator and said additional adjustable element for moving the latter in a direction to turn said guiding element on its pivot for also adjusting said device.

5. Apparatus for controlling an adjustable device for affecting a circuit, comprising a support, a set-up handle adjustably mounted on the support for selecting any desired adjustment of said device, a slideable element actuated to a position corresponding to the position of the handle, a guiding element pivoted on said slideable element, a second slideable element engaging said guiding element for adjusting said device upon movement of said handle, an additional adjustable element having a pin and slot connection with one end of said guiding element for normally restraining said guiding element from turning on its pivot, an actuator, and adjustable coupling means between said actuator and said additional adjustable element for making the actuator effective or ineffective in moving said additional adjustable element in a direction to turn said guiding element on its pivot for also adjusting said device.

6. Apparatus for controlling an adjustable device for affecting a circuit, comprising a support, a set-up handle adjustably mounted on the support for selecting any desired adjustment of said device, a movable element, means controlled by movement of said handle for actuating said movable element in a linear direction to a position corresponding to the position of said handle, a guiding element carried by and bodily movable as a whole with said movable element in said direction and normally inclined to said direction of movement at the same angle during said movement, a third element slidably engaging said

guiding element, means actuated by said third element for adjusting said device upon movement of said handle, and means engaging said guiding element for adjusting the guiding element on said movable element in a different direction from said linear direction for thereby also adjusting said device by movement of said third element.

7. Apparatus for controlling an adjustable device for affecting a circuit comprising a support, a set-up handle adjustably mounted on the support for selecting any desired adjustment of said device, a movable element, means controlled by movement of said handle for actuating said movable element in a linear direction to a position corresponding to the position of said handle, a guiding element pivoted on and carried by and bodily movable as a whole with said movable element in said direction and normally inclined to said direction of movement at the same angle during said movement, a third element slidably engaging said guiding element in a direction from its pivot to other portions thereof, means actuated by said third element for adjusting said device according to the adjustment of said handle, and means engaging said guiding element for turning the same on its pivot for thereby also adjusting said device by movement of said third element.

8. Apparatus for controlling an adjustable device for affecting a circuit, comprising a support, a set-up handle adjustably mounted on the support for selecting any desired adjustment of said device, a movable element, means controlled by movement of said handle for actuating said movable element in a linear direction to a position corresponding to the position of the handle, a guiding element pivoted on and carried by and bodily movable as a whole with said movable element in said direction and normally inclined to said direction of movement at the same angle during said movement, a slideable element engaging said guiding element, means actuated by said slideable element for adjusting said device upon movement of said handle, restraining means for normally holding said guiding element from turning on its pivot, an actuator for controlling movement of said restraining means, and an enabling device for making movement of said actuator effective or ineffective in moving said restraining means.

9. Apparatus for controlling an adjustable device for affecting a circuit comprising a support, a set-up handle adjustably mounted on the support for selecting any desired adjustment of said device, a movable element, means controlled by movement of said handle for actuating said movable element in a linear direction to a position corresponding to the position of the handle, a guiding element pivoted on and carried by and bodily movable as a whole with said movable element in said direction and normally inclined to said direction of movement at the same angle during said movement, a third element slidably engaging said guiding element from its pivot to other portions thereof, means actuated by said third element for adjusting said device according to the position of said handle, restraining means for normally holding said guiding element from turning on its pivot, an actuator for controlling movement of said restraining means, and an enabling device for making movement of said actuator effective or ineffective in moving said restraining means.

10. Apparatus for controlling an adjustable de-

vice for affecting a circuit comprising a support, a set-up handle adjustably mounted on the support for selecting any desired adjustment of said device, a movable element, means controlled by movement of said handle for actuating said movable element in a linear direction to a position corresponding to the position of the handle, a guiding element pivoted on and carried by and bodily movable as a whole with said movable element in said direction and normally inclined to said direction of movement at the same angle during said movement, a slidable element engaging said guiding element, means actuated by said slidable element for adjusting said device upon movement of said handle, a holding element having a slotted portion for engaging said guiding element for holding the same from turning on its pivot, an actuator for moving said holding element for turning said guiding element on its pivot, and an enabling device between said actuator and said holding element for causing movement of said actuator to be effective or ineffective in moving said holding element.

11. Apparatus for controlling an adjustable element for affecting a circuit comprising a guide inclined at an angle to the direction of movement of said element, a movable element connected with said guide for moving said guide in a linear direction at an angle to the inclination of said guide, a slidable connection between said guide and said adjustable element, and means for maintaining said guide at said inclined angle upon actuation by said movable element and for changing said angle for also adjusting said adjustable element, said means comprising a coupling for making the means effective or ineffective in changing said angle and for setting said guide at said inclined angle when said means is made ineffective.

12. Apparatus for controlling an adjustable element for affecting a circuit comprising a guide inclined at an angle to the direction of movement of said element, a movable element connected with said guide for moving said guide in a linear direction at an angle to the inclination of said guide, a slidable connection between said guide and said adjustable element, and means for maintaining said guide at said inclined angle upon actuation by said movable element and for changing said angle for also adjusting said adjustable element, said means comprising a coupling for making the means effective or ineffective in changing said angle and for adjusting said guide to an angular position corresponding to that imposed by said means when said means is made effective.

13. Apparatus for controlling a plurality of adjustable devices for affecting their respective circuits comprising a plurality of adjustable handles and means respectively controlled thereby for controlling said devices respectively, means comprising a plurality of rotatable actuators for also controlling said devices respectively independently of movement of said handles, a master element for actuating said actuators simultaneously, and enabling means for each actuator respectively for making the movement of its respective actuator by said master element effective or ineffective in adjusting said devices, said enabling means comprising a slidable element for each actuator movable to coincide with the axis of its actuator or to engage its actuator at a distance from said axis.

14. Apparatus for controlling a plurality of separately adjustable circuit controlling devices for

individually affecting their circuits respectively, comprising a plurality of set-up handles and means respectively controlled thereby for adjusting said devices respectively, master means comprising a common element for simultaneously moving said devices from their various positions as determined by adjustment of said handles to different desired positions independently of movement of said handles, a master handle, mechanism between said master handle and said common element for actuating said element upon movement of said master handle, said mechanism comprising a pivoted guiding element bodily movable as a whole with its pivot by said master handle in a linear direction and said guiding element being normally inclined to said direction of movement at the same angle during said movement for actuating said common element, means comprising a grand master element for turning said guiding element on its pivot for also actuating said common element, and means for making movement of said ground master element effective or ineffective in turning said guiding element on its pivot.

15. Apparatus for controlling a plurality of separately adjustable circuit controlling devices for individually affecting their circuits respectively, comprising a plurality of set-up handles and means respectively controlled thereby for adjusting said devices respectively, master means comprising a common element for simultaneously moving said devices from their various positions as determined by adjustment of said handles to different desired positions independently of movement of said handles, a master handle, mechanism between said master handle and said common element for actuating said element upon movement of said master handle, said mechanism comprising a pivoted guiding element bodily movable as a whole with its pivot by said master handle in a linear direction and said guiding element being normally inclined to said direction of movement at the same angle during said movement for actuating said common element, means comprising a grand master element for turning said guiding element on its pivot for also actuating said common element, and means for making movement of said ground master element effective or ineffective in turning said guiding element on its pivot.

16. Apparatus for controlling a plurality of separately adjustable circuit controlling devices for individually affecting their circuits respectively, comprising a plurality of set-up handles and means respectively controlled thereby for adjusting said devices respectively, master means comprising a common element for simultaneously moving said devices from their various positions as determined by adjustment of said handles to different desired positions independently of movement of said handles, a master handle, mechanism between said master handle and said common element for actuating said element upon movement of said master handle, said mechanism comprising a pivoted guiding element bodily movable as a whole with its pivot by said master handle in a linear direction and said guiding element being normally inclined to said direction of movement at the same angle during said movement for actuating said common element, means comprising a grand master element for turning said guiding element on its pivot for also actuating said common element, and means for making movement of said ground master element effective or ineffective in turning said guiding element on its pivot.

17. Apparatus for controlling a plurality of separately adjustable circuit controlling devices for individually affecting their circuits respectively, comprising a plurality of set-up handles and means respectively controlled thereby for adjusting said devices respectively, master means comprising a common element for simultaneously moving said devices from their various positions as determined by adjustment of said handles to different desired positions independently of movement of said handles, a master handle, mechanism between said master handle and said common element for actuating said element upon movement of said master handle, said mechanism comprising a pivoted guiding element bodily movable as a whole with its pivot by said master handle in a linear direction and said guiding element being normally inclined to said direction of movement at the same angle during said movement for actuating said common element, means comprising a grand master element for turning said guiding element on its pivot for also actuating said common element, and means for making movement of said ground master element effective or ineffective in turning said guiding element on its pivot.

said guiding element on its pivot for also actuating said common element, and means for making movement of said grand master element effective or ineffective in turning said guiding element on its pivot comprising a rotatable actuator and a coupling between said actuator and said guiding element adjustable from the axis of said actuator to a distance from said axis.

17. Apparatus for controlling a plurality of sets of separately adjustable circuit controlling devices comprising a plurality of set-up handles in each set and means respectively controlled thereby for adjusting said devices respectively, means comprising a master shaft for each set for moving said devices of its set independently of other of said sets and independently of movement of the handles of its set, a master handle for each set respectively, means comprising a pivoted guiding element for each set respectively bodily movable as a whole with its pivot by its master handle in a linear direction and said guiding element being normally inclined to said direction of movement at the same angle during said movement for actuating the master shaft of its set, a grand master shaft for each set respectively, means comprising a rotatable element actuated by each of said grand master shafts for turning its respective said guiding element on its pivot for actuating its respective master shaft, and means comprising a grand master handle for actuating said grand master shafts simultaneously.

18. Apparatus for controlling a plurality of sets of separately adjustable circuit controlling devices, comprising a plurality of set-up handles in each set and means respectively controlled thereby for adjusting said devices respectively, means comprising a master shaft for each set for moving said devices of its set independently of the other of said sets and independently of movement of the handles of its set, a master handle for each set respectively, means comprising a pivoted guiding element for each set respectively bodily movable as a whole with its pivot by its master handle in a linear direction and said guiding element being normally inclined to said direction of movement at the same angle during said movement for actuating the master shaft of its set, a grand master shaft for each set respectively, means comprising a rotatable element actuated by each of said grand master shafts for turning its respective said guiding element on its pivot for actuating its respective master shaft, means comprising a grand master handle for actuating said grand master shafts simultaneously, and means for rendering movement of said rotatable elements individually effective or ineffective in actuating their respective guiding elements.

19. Apparatus for controlling a plurality of sets of separately adjustable circuit controlling devices, comprising a plurality of set-up handles in each set and means respectively controlled thereby for adjusting said devices respectively, means comprising a master shaft for each set for moving said devices of its set independently of other of said sets and independently of movement of the handles of its set, a master handle for each set respectively, means comprising a pivoted guiding element for each set respectively bodily movable as a whole with its pivot by its master handle in a linear direction and said guiding element being normally inclined to said direction of movement at the same angle during said movement for actuating the master shaft of its set, a grand master shaft for each set respectively, means

comprising a rotatable element actuated by each of said grand master shafts for turning its respective guiding element on its pivot for actuating its respective master shaft, means comprising a grand master handle for actuating said grand master shafts simultaneously, and means adjustable to and from the axis of said rotatable elements respectively for rendering said rotatable elements individually effective or ineffective in actuating their respective guiding elements.

20. Apparatus for controlling an adjustable device for affecting a circuit comprising a pivoted inclined guiding element, means comprising an element slidably engaging said pivoted guiding element for adjusting said device, an adjustable element for slidably moving said pivoted guiding element bodily as a whole in a linear direction at an angle to the inclination of said pivoted guiding element for adjusting said device, and a second adjustable element for rotating said pivoted guiding element for also adjusting said device.

21. Apparatus for controlling an adjustable device for affecting a circuit comprising a support, two set-up handles adjustably mounted on said support for selecting any desired adjustment of said device, two slidable elements each having inclined guides, said slidable elements being mounted on said support, means controlled by said handles respectively for adjusting said slidable elements to positions corresponding to the respective positions of said handles, additional slidable elements having portions respectively engaging said inclined guides and actuated by movement of said first named slidable elements, an additional guiding element having its opposite ends respectively engaged by said additional slidable elements for adjusting the opposite ends of said additional guiding element, and means slidably engaging said additional guiding element for adjusting said device.

22. Apparatus for controlling an adjustable device for affecting a circuit comprising a support, two set-up handles adjustably mounted on said support for selecting any desired adjustment of said device, two slidable elements mounted on said support, means controlled by said handles respectively for adjusting said slidable elements to positions corresponding to the respective positions of said handles, two guiding elements pivotally mounted on said slidable elements respectively, additional slidable elements having portions respectively engaging said guiding elements and actuated by movement of said first named slidable elements, an additional guiding element having its opposite ends respectively engaged by said additional slidable elements for adjusting the opposite ends of said additional guiding element, means slidably engaging said additional guiding element for adjusting said device, and two actuators engaging said pivoted guiding elements respectively for turning them on their pivots for also adjusting said additional slidable elements.

23. Apparatus for controlling an adjustable device for affecting a circuit comprising a support, two set-up handles adjustably mounted on said support for selecting any desired adjustment of said device, two slidable elements mounted on said support, means controlled by said handles respectively for adjusting said slidable elements to positions corresponding to the respective positions of said handles, two guiding elements pivotally mounted on said slidable elements respectively, additional slidable elements having portions respectively engaging said guiding elements and

actuated by movement of said first named slide-
able elements, an additional guiding element hav-
ing its opposite ends respectively engaged by said
additional slideable elements for adjusting the op-
posite ends of said additional guiding element,
means slidably engaging said additional guiding
element for adjusting said device, two actuators

engaging said pivoted guiding elements respec-
tively for turning them on their pivots for also
adjusting said additional slideable elements, and
means for making movement of said actuators
effective or ineffective in turning said pivoted
guiding elements on their pivots.

GEORGE M. STAPLETON.
